(57) **CLAIM**

The ornamental design for a grab bar, as shown and described.

DESCRIPTION

In a preferred embodiment, the nature of this product is as a grab bar mountable along a shower area wall.

FIG. 1 is a top, right, frontal perspective view of a grab bar embodying my new design;

FIG. 2 is a top plan view thereof;

FIG. 3 is a front elevational view thereof;

FIG. 4 is a right side elevational view thereof;

FIG. 5 is a left side elevational view thereof;

FIG. 6 is a rear elevational view thereof;

FIG. 7 is a bottom plan view thereof; and,

FIG. 8 is a top plan view of a second embodiment, which is a mirror image of the first embodiment. Hence, the front elevational view thereof is a mirror image of FIG. 3, the left side elevational view thereof is a mirror image of FIG. 4, the right side elevational view thereof is a mirror image of FIG. 5, the rear elevational view thereof is a mirror image of FIG. 6, and the bottom plan view thereof is a mirror image of FIG. 7.

The broken line representations in the figures are for the purpose of illustration only, and form no part of the claimed design.
